UNITED STATES PATENT OFFICE.

VIRGIL M. HADDON, OF OMAHA, NEBRASKA.

OPERATING MECHANISM FOR DUMPING TRUCKS.

1,411,346.

Specification of Letters Patent.

Patented Apr. 4, 1922.

Application filed February 14, 1921. Serial No. 444,979.

To all whom it may concern:

Be it known that I, VIRGIL M. HADDON, a citizen of the United States, residing at Omaha, in the county of Douglas and State 5 of Nebraska, have invented certain new and useful Improvements in Operating Mechanism for Dumping Trucks, of which the following is a specification.

This invention relates to operating mechanism for dumping trucks. While the mechanism may be used generally, it is particularly adapted for use in connection with the dumping truck shown and described in U. S. Letters Patent issued to Virgil M. Haddon, No. 1,359,363, dated Nov. 16, 1920, and has for its object to provide means which will be convenient in use for swinging the box to a dumped position and means for maintaining the box at selected degrees 20 of inclination to permit spreading the contents on the ground; also means for moving the box and automatically maintaining it in a horizontal position; also the invention includes certain adjustable features and the 25 use of a reversible locking-bar found to be of advantage in the control of the movements of the box.

In the accompanying drawing which illustrates the invention, Fig. 1 is a view in side 30 elevation showing the box in a horizontal position with the operating mechanism mounted thereon. Figs. 2 and 3 are details showing an adjustable mounting for a spring latch-bar. Figs. 4 and 5 are details showing 35 a mounting of a locking-bar upon a hand-lever to permit reversal of said bar. Fig. 6 is a side view showing the box in a dumped position and showing the operating mechanism.

Referring now to the drawing for a more particular description, the invention is illustrated and described in connection with the frame 1, rear axle 2 and box 3 of a dumping truck, said frame being provided with 45 a superframe 4 and the box being mounted in an over-frame 5 having a pivotal mounting 6 upon the super-frame to permit swinging movements above the axle 2, said box having a bottom inclined downwardly toward its rear end, and provided with a door 7 pivotally mounted near its top, as indicated at 8, upon the sides to make a closure 50 of the rear, open end of the box.

Numeral 9 indicates a hand-lever pivotally mounted, as indicated at 10, upon a bracket 11 which is provided on the super-

frame, and at 12 is indicated a link having a pivotal mounting 13 for its upper end upon a bracket 14 which is secured to the side of the frame 5, at the front part thereof, its lower end being mounted upon a pivot-member 15 between the ends of the lever 9. At 16 is indicated a push-and-pull bar, its front end being mounted upon the pivot-member 15, and its rear end having a 60 pivotal mounting 17 upon the door 7, and by use of the hand lever the front end of the box may be swung upwardly for dumping, the door 7 being automatically opened. Since the parts thus described are shown and 70 claimed in the Letters Patent above mentioned, no claim is made for these features in the present application.

In order that the front end of the box may be maintained in an elevated position 75 after it has been swung upwardly and that the box may be maintained at different degrees of inclination I provide a locking-bar 18 provided, at one of its sides, with a plurality of projections 19, said bar being 80 disposed within a staple or loop 20 which is secured to the side of the frame 5, near the top thereof, and having its lower end mounted, as indicated at 21, upon the hand lever, and it will be understood that when 85 the front end of the box has been swung upwardly the bar 18 will move in the loop 20, and its projection or one of said projections will become caught upon the lower part of said loop, to maintain the box in a dumped 90 position.

The advantages to be derived in maintaining the box at various degrees of inclination will be appreciated, since it is occasionally necessary for an operator to scrape 95 plastic or adhesive material from the box and it is obvious that the box, for this operation, should be maintained stationary in dumped position; also when the dumping truck is used in connection with the work 100 of paving, it is often desirable to spread the material on the ground, the box being maintained at a lesser degree of inclination while the truck is moved forwardly.

The mounting of the bar 18 upon the hand 105 lever is such that it may be disposed with its rectilinear side α in engagement with the loop 20, this being for the purpose of preventing the box from being held in a dumped position, and being useful in instances where 110 brick, stone or non-adhesive material is to be dumped, a leaf-spring 22 (Figs. 4, 5.)

being secured to one of the sides of the bar 18 and having an aperture *a* to permit it to be traversed by the pivot 21 of the hand lever 9, a pin *b* being used for securing the 5 spring upon said pivot, and it will be understood that the mounting of the bar 18 may be readily changed so that its projections 10 will be disposed uppermost and that these 15 projections will not engage the lower part of the loop 20, and since the rectilinear side *x* will then be in engagement with the lower part of said loop, the box, when its front 20 end has been swung upwardly, will not be maintained in its dumped position, the bar 18 when thus disposed operating simply to prevent any sidewise swinging movement of the hand lever. This feature of adjustment which permits reversal of the locking-bar is of great advantage since it may be required to haul and dump non-adhesive as 25 well as adhesive material.

Numeral 23 indicates a catch which is secured to the front end of the super-frame 4, and at 24 is indicated a spring-latch-bar 25 which is secured to the front part of the over-frame 5 and which projects downwardly therefrom for engaging the catch 23 to maintain the box in a horizontal position, and at 25 is indicated a crank-handle which 30 is mounted upon the hand lever, and any suitable, flexible member 26 may be used for connecting the crank-handle with the latch-bar; and in operation, to cause dumping of the box, the latch-bar is released from the 35 catch 23 by manual use of member 25, the operator thereafter swinging the hand-lever upwardly, the link 12 thereby being moved for elevating the front end of the box, and the bar 16 being moved to cause the door 40 to open.

It will be appreciated that the spring latch-bar should engage the catch accurately to prevent vibration of the box and to prevent any vertical movement of the box independently of the frame of the truck during the operation of loading and during the movements of the truck, and since the contacting parts of the latch-bar and catch 45

become worn with use, it is necessary to provide for adjustments to be described.

As best shown in Figs. 2 and 3, the front part of the over-frame 5 is provided with a grooved plate or rack 27 having a slot 28 formed therein for receiving bolts 29 which are provided for the latch-bar 24, the latter being provided with ridges, as shown, adapted to engage in the grooves of the plate 27, and by use of the means described the latch-bar may be moved lengthwise so that its head will be firmly seated upon the catch, 60 and the bolts 29 being applied and adjusted, any rocking movements of the box relative to the superframe 4, while the box is disposed in a horizontal position, will be prevented.

While I have shown and described construction in detail, I do not wish to be understood as limiting myself in this respect, and changes in form, size, proportion and minor details may be made; said changes to 70 be determined by the scope of the invention as claimed.

I claim:

In combination, a vehicle frame provided with a catch, a box provided with a staple, 75 a latch mounted on the box adapted to have longitudinal adjustments for engaging the catch to normally maintain the box in stationary relation with the frame, a hand lever pivotally mounted on the frame, a flexible member carried by said hand lever for releasing the latch from said catch, a link 80 connecting the hand lever with said box, a locking-bar carried by the hand lever, said hand lever being movable for moving the 85 box and for moving the locking-bar, a part of said bar moving into engagement with the staple for maintaining the box in inclined relation with the frame.

In testimony whereof, I have affixed my 90 signature in presence of two witnesses.

VIRGIL M. HADDON.
